UNITED STATES PATENT OFFICE.

GEORGE L. TULLY, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

OPHTHALMIC MOUNTING.

Application filed November 30, 1923. Serial No. 677,844.

The present invention relates to an improved form of ophthalmic mounting and has particular reference to the so-called all celluloid frame.

An important object of the present invention is to provide a mounting of this nature wherein a saddle form of bridge is used in such a manner that the said bridge may be adjusted as desired.

Heretofore the so-called all celluloid frames have been so constructed that it has been impossible to adjust the bridge to the patient's face as has been desirable, and this invention has, therefore, for an important object thereof, to do away with the inconvenience of this form of mounting by providing a form of bridge that will not in any way detract from the beauty of this type of mounting, but at the same time will be subject to adjustment.

Another very important object of the invention is to provide a mounting of this nature that will be strong, durable, very simple and inexpensive in construction and that is well adapted for the uses for which it is desired.

Other objects and advantages of the invention will become apparent during the course of the following description.

In the drawings, wherein like numerals are employed to designate like parts throughout the same,

Figure 1 is a rear elevation of my improved form of ophthalmic mounting,

Figure 2 is a fragmentary sectional view thereof illustrating one form of bridge anchoring means,

Figure 3 is a top plan view of the mounting, and

Figure 4 shows a slightly modified form of bridge anchoring means.

In the drawings, wherein for the purposes of illustration is shown the preferred embodiment of my invention, the numeral 5 designates a mounting which comprises the eyes 6, improved bridge 7 and end pieces 8.

My improved form of bridge comprises a metallic inner member 9, which is shaped as is desired and has the curved portions 10 to facilitate the adjustment, while the ends thereof terminate in the barb 11. The metallic inner core 9 of the bridge is covered with a cellulose composition such as zylonite 12. The cellulose composition 12 may be

applied either by spraying, dipping or the like, in a liquid composition, or the core 9 may be inserted through a length of tube stock before it has been bent. After the core 9 has been placed within a length of tube stock both the cellulose composition 12 and metallic bridge may be formed to the desired configuration, but I desire that the adjusting portions 10 be provided to facilitate the adaptation of the bridge to numerous types of faces. The eyes 6 are preferably heated to a semi-plastic condition, after which the barbed ends 11, which is to be understood are not covered with the cellulose composition 12, are driven within the same in such a manner that they will become firmly embedded in the eyes, and after the eye portions 6 have been allowed to cool again and set up, the bridge 7 will be securely anchored in position. It will, of course, be understood that the barbed ends 11 will prevent any displacement of the bridge 7 with respect to the eye pieces 6. The cellulose composition 12 may then be cemented to the eye portions 6 as at 13, thus forming an unrecognizable joint between the two so that a mounting will be provided that will in every way resemble the heretofore so-called all celluloid mounting with the additional desirable feature that the bridge 7 may be adjusted.

In Figure 4 a slight modification of the anchoring means is shown, wherein a form of plate 14 is carried by the outer extremities of the inner core 9 of the bridge 7. The plate 14 is adapted to be received within a suitable recess 15 which is communicated with the lens seat 16, said plate 14 being so disposed that it will not in any way interfere with the reception of the lens 16 when the mounting is in use. The plate 14 may be held in place by a suitable cement so as to form a rigid anchor for the bridge, and if it is desired, small apertures 17 may be so provided in the plate 14 that additional means will be had to form a good anchor.

In accordance with the above invention, it will be seen that I have devised means wherein an adjustable form of an all celluloid mounting may be had whereby the bridge may be so adjusted that it will accommodate itself to various shaped and sized faces, thus making it much easier to fit such a form of mounting to a patient while at the same time

the patient will experience more comfort when wearing this type of mounting.

It is to be understood that the form of my invention herewith shown and described is to be taken as the preferred embodiment of the same, and that various changes in the shape, size and arrangement of parts may be resorted to without departing from the spirit of the invention or the scope of the subjoined claims.

Having thus described my invention, I claim:

1. An ophthalmic mounting of the character described comprising eye pieces formed from cellulose composition material having recesses formed therein, an adjustable bridge interposed therebetween, plates carried by the adjustable bridge, said plates being adapted to be received within the recesses formed within the eye pieces and a cellulose composition covering arranged on the adjustable bridge.

2. In a device of the character described,

a pair of non-metallic lens rims having a lens groove therein and an internal recess 25 communicating with the lens groove, a metallic bridge having a terminal plate on each end inserted in the internal recess, and means for holding the terminal plates in the recesses.

3. In a device of the character described, a pair of non-metallic lens rims having a lens groove therein and an internal recess 35 communicating with the lens groove, a metallic bridge having terminal plates extending into the recesses and cementitious means for securing the plates in the recesses.

4. In a device of the character described, a pair of non-metallic lens rims having a lens groove and an internal recess communicating with the lens groove, a metallic bridge having recessed terminal plates extending into the recesses, and a cement securing the plates in the recesses, said cement extending 40 into the recesses in the plates.

GEORGE L. TULLY.
